UNITED STATES PATENT OFFICE.

AIKEN HAMAN, OF SAN FRANCISCO, CALIFORNIA.

WHEEL-FENDER FOR RAILWAY-CARS.

SPECIFICATION forming part of Letters Patent No. 268,484, dated December 5, 1882.

Application filed September 4, 1882. (No model.)

To all whom it may concern:

Be it known that I, AIKEN HAMAN, a citizen of the United States, residing in the city and county of San Francisco, State of California, have made and invented a new and useful Improvement in Fenders or Guards for Wheels of Cars and Dummies; and I do hereby declare that the following is a full, clear, and exact description of the same, reference being had to the accompanying drawings.

My invention relates to a means of preventing accidents on street-railroad cars and dummies.

It consists in the novel construction and application of a device to the front of the car, by which persons crossing the track before it are prevented from being injured if struck by the fender, and also, in connection therewith, a novel guard for the wheels, by which persons falling under the car at the sides are prevented from being run over, the two devices co-operating together to form an effective and certain protection for such vehicles.

My invention is designed more particularly for use on the dummies or engines of endless-cable railroads, wherein accidents to persons are of frequent occurrence.

The following description fully explains the nature of my said invention and the manner in which I proceed to construct, apply, and use it, reference being made by letters and figures to the accompanying drawings, in which—

Figure 1 is a side elevation of my improved fender attachment for street-cars, shown partly in section at the front. Fig. 2 is a front view. Fig. 3 is a plan or top view. Fig. 4 shows the guard or fender attachment for the wheels. Fig. 5 is a view of the fender-frame detached from the front of the truck.

The guard or fender A, which I apply to the front of a car or dummy, consists essentially of a soft yielding surface, constructed of a framework of slats mounted on spiral springs, stuffed or padded, after the manner of a mattress or bed-bottom, and covered with leather, rubber, or canvas. This frame-work is attached to the end of the truck or frame of the car, and projects forward in front a suitable distance, presenting sufficient surface to catch and receive a person when struck by the front end. At this part the front is inclined, and is brought

down close to the surface of the road, so that it just clears the track. Its construction and mode of attachment, as illustrated in the accompanying drawings, are as follows.

A light frame-work of bars, A A B B, supports a number of slats, C C, mounted in springs D D, which are arranged horizontally, one above the other, to the desired height. The forward end of the frame has the slats placed in slanting position to produce the inclined or wedge-shaped end E. By means of short standards F, secured to the side timbers of the track X, and the upright rods G of the frame, connection and attachment is made to the truck. For this purpose there are eyes f f provided in the standard to secure the end of the rods, and from these points the frame is suspended. The surface of this frame-work is stuffed or padded with some suitable substance—such as is employed for upholstering purposes—and is then covered with canvas, leather, or other material having the necessary qualities to stand exposure to the weather. By this construction the fender is made an independent structure, capable of being attached to the end of a car or a dummy truck, and of being taken off and changed from one end to the other, as required; or each end of the truck can be provided with such a fender, to be left on permanently. In such case an opening, H, is provided in the center of the fender for the draw-head W of the coupling. This opening is in the form of a pocket, as shown in Fig. 5, so that the surface of the fender projects out beyond the head or both sides. This opening H may be closed by a slide, y, so as to produce an unbroken surface across the perpendicular front of the fender in that end of the dummy which is presented to the front.

If required, the extreme front end of the fender-frame can be supported by small bearing-wheels to run on the rails, and a certain perpendicular yielding action in the fender can be given by placing around each rod G a coil-spring, I, bearing against the eye f of the standard at one end, and on a shoulder, j, on the rod G at the other end. In addition to this means of preventing persons from getting in under the front of a car, I also find it important to provide special guards to the wheels, by which it will be impossible for any one to

slip in under the car at the sides to get in under the wheels. This device I construct in the manner shown in Figs. 1 and 4. Upon the lower end of a short rod, 1, I form or secure a covered shoe, 2, about equal in width to the width of the tread and flange of a car-wheel, and by means of a bracket, 3, secured to the axle-box or other convenient stationary part, I support one shoe in front and another behind each wheel. A bearing-roller, 4, in the bottom of the shoe may be used to prevent rubbing contact with the track, or may be applied to run in continual contact with the rail. The shoe can be held in proper relation and position, however, without employing this roller. A spring, 5, is applied to the rod 1 to allow the shoe to ride over any inequality or obstruction on the track that may be small enough to pass under the edge of the shoe. Such a guard is simple, effective, and readily applied. It is formed of metal, and may be padded or covered, if desired.

These two devices, when applied in such manner to the truck and wheels of a cable-railway dummy, afford complete and efficient protection to pedestrians, as well as to the riders on the dummy, from accidents by being run into or run over by such vehicle.

Having thus fully described my invention, what I claim, and desire to secure by Letters Patent, is—

1. A fender for street-cars and dummies, consisting of a frame-work, A B, extended forward at a low level, so as to form an approximately horizontal step or seat, as described, 35 suitably stuffed or padded, and covered, and adapted to be attached to and covered by the front end of the car or dummy truck, substantially as described.

2. The improved fender consisting of the 40 frame A B, with spring-slats C D; and a suitable stuffing and covering, having the recess H for the draw-head and a means for attaching it to the front of a car or dummy.

3. The guard attachment for car-wheels, consisting of the bracket 3, the rod 1, the shoe secured thereto, and the yielding spring 5, 45 substantially as described.

Witness my hand and seal.

AIKEN HAMAN. [L. S.]
